UNITED STATES PATENT OFFICE.

GEORGE D. CARR, OF DETROIT, MICHIGAN.

COMBINATION DOOR-LOCK.

1,242,140.

Specification of Letters Patent.

Patented Oct. 9, 1917.

Application filed September 21, 1915. Serial No. 51,819.

To all whom it may concern:

Be it known that I, GEORGE D. CARR, a citizen of the United States, residing at Detroit, in the county of Wayne and State of Michigan, have invented certain new and useful Improvements in Combination Door- Locks; and I do hereby declare the following to be a full, clear, and exact description of the invention, such as will enable others skilled in the art to which it appertains to make and use the same.

This invention has for its primary object to provide an improved type of combination lock especially designed for use in connection with house doors and embodying means whereby the latch bolt may be locked or released from either the inside or outside of the door.

With this and other objects in view, the invention consists in the novel construction, arrangement and formation of parts as will be hereinafter specifically described, claimed and illustrated in the accompanying drawings, in which:

25 Figure 1 represents a fragmental side elevation of a door, illustrating the improved combination lock applied to use thereon,

30 Fig. 2 represents a fragmental edge elevation of the door illustrating the lock applied thereto,

35 Fig. 3 represents a side elevation of the lock removed, the side plate being also removed,

40 Fig. 4 represents a side elevation similar to Fig. 3 illustrating the latch bolt in retracted position,

Fig. 5 represents a transverse sectional view on the line 5—5 of Fig. 3,

45 Fig. 6 represents a side elevation of the lock casing, the parts of the lock being removed,

Fig. 7 represents a fragmental detail sectional view through the lock, illustrating the means for retaining the tumblers against loose movement, and

50 Fig. 8 represents a side elevation of the several tumblers and spacing elements of the lock removed.

Referring to the drawing in detail, wherein similar reference numerals designate corresponding parts, throughout the several views, the numeral 10 indicates generally the casing of the lock, the outer end wall 55 of which is extended and apertured, as at 11, to receive screws, or equivalent means,

whereby the lock is secured in position in the recess formed in the free edge of a door 12. One side wall 13 of the casing 10 is preferably removable, whereby when the lock is removed from the door access may be had to the interior thereof.

A sleeve 14 having an angular bore 15 is rotatably mounted in the side walls of the casing 10 and is adapted to receive the shank 65 of a door knob 16. The sleeve 14 is formed with a radially projecting arm 17 engaged within a recess 18 formed in an L-shaped member 19, slidably mounted in a passage 20 formed by partitions 21 arranged in the casing 10. The upper angularly directed end 22 of the slidable member 19 is engaged with one of a pair of laterally projecting ears 23 formed upon the slidable bolt 24. The outer extremity of the bolt 24 is preferably beveled and the inner end thereof is formed with a longitudinal slot 25 slidably receiving a stop member 26 formed integral with the casing 10 and constituting an abutment for one end of a spring 27 engaged in the slot 25 and normally retaining the bolt 24 in extended position.

One of the partitions 21 is extended to provide a substantially circular housing 29 for the tumblers of the lock to be hereinafter described, and said housing, at diametrically opposed points is formed with recesses 30. The flange or housing 29 is also formed with a recess 31 of adequate width to slidably receive the inner extremity of the bolt 24.

A plurality of tumblers 32, 33 and 34 are rotatably mounted in the housing 29 and the two outer members are normally retained in spaced relation to the intermediate member 33 by spacing elements 35, which latter are formed with oppositely directed ribs or projections 36 engaged in the recesses 30 of the housing 29 to lock the spacing elements against rotary movement therein. The spacing elements 35 are cutaway, as at 37, to accommodate sliding movement of the bolt 24. The end tumblers 32 and 34 are formed with axial enlargements 38 and 39, respectively, which are rotatably mounted in openings formed in the sides of the casing 10. Each of the several tumblers is formed with a recess 40 adapted, when the several recesses are moved into alignment with the cutaway portion 31 of the housing or flange 29, to permit the bolt 24 to be moved inwardly to inoperative position, as illustrated

in Fig. 4. The outer tumblers 32 and 34 are formed with inwardly directed lugs or pins 41 and 42, respectively, which are adapted to engage, during rotation of said tumblers, a pin 43 secured in and projecting laterally of the opposite side faces of the intermediate tumbler 33. Shanks 44 are removably secured in the outer tumblers 32 and 34 and project oppositely through apertures 45 formed in the door 12. Plates 46 are secured to the door 12 over the apertures 45 and are formed with apertures 47 having internal shoulders or flanges 48 receiving the inner portions of operating knobs 49. Plates 50 are secured to the inner ends of the knobs 49 by screws 51, or equivalent means, and are engaged with the shoulders or flanges 48 to secure the knobs against removal from the plates 46. The knobs are also formed with recesses 52 non-rotatably receiving the shanks 44.

The partition 21 is formed with a recess 54 receiving a retaining element 55, which is normally retained in engagement with the circumferential edges of the tumblers 32, 33 and 34 by the tension of a spring 56. Each of the several tumblers is formed with a notch 57 so arranged that when the several recesses 40 are moved into alinement to permit the bolt 24 to be retracted, the recesses or notches 57 are moved into alinement and the retaining element 55 moved forwardly under the influence of the spring 56 and engaged in said notches, thus resiliently retaining the several tumblers in adjusted position.

What I claim is:

A combination lock including a casing, a circular housing in said casing having a relatively large recess and relatively small diametrically opposed recesses therein, a lug

carried by the casing projecting into the relatively large recess in the housing, a bolt slidably mounted in the casing, movable into the relatively large recess in the housing 45 and having a slot in its inner end receiving said lug, a spring confined between the lug and bolt, a plurality of disk shaped tumblers rotatably mounted in the housing having recesses adapted to be moved into registration with the relatively large recess in the housing to receive the inner terminal of said bolt, annular spacing members interposed between the tumblers having portions cut away to receive said bolt, diametrically opposed projections on said spacing members engaged in the relatively small recesses in the housing, said tumblers each having a transverse notch in its periphery, said circular housing being provided with a groove 60 forming a guide channel, a retaining element slidably mounted in said guide channel and adapted to engage in the notches in the tumblers, and a spring normally holding said retaining element in an extended position to hold said retaining element in engagement with the tumblers, the transverse notches and the recesses which receive the bolt in said tumblers being so arranged in relation to each other that when the retaining element is received in the transverse notches the recesses are in registration with the relatively large recess in the housing, whereby the tumblers are resiliently held in position. 70 75

In testimony whereof I affix my signature in presence of two witnesses:

GEORGE D. CARR.
